(57) **CLAIM**

We claim the ornamental designs for a LED troffer fixture, as shown and described.

DESCRIPTION

FIG. 1 is a front view showing an embodiment of our new design for a LED troffer fixture;

FIG. 2 is a back view of the LED troffer fixture of FIG. 1; FIG. 3 is a right side view of the LED troffer fixture of FIG. 1;

FIG. 4 is a left side view of the LED troffer fixture of FIG. 1;

FIG. 5 is a bottom view of the LED troffer fixture of FIG. 1;

FIG. 6 is a top view of the LED troffer fixture of FIG. 1; FIG. 7 is a bottom perspective view of the LED troffer fixture of FIG. 1; and,

FIG. 8 is a top perspective view of the LED troffer fixture of FIG. 1.

The portions shown in broken lines are not part of the claimed design but show the environment in which the design is associated.

1 Claim, 6 Drawing Sheets
